(57) **CLAIM**

We claim the ornamental design for a film dispensing tool for stationery, as shown and described.

DESCRIPTION

FIG. 1 is a front view of the film dispensing tool for stationery showing our new design, the hash marks appearing in the drawings indicating transparent sections of the design;

FIG. 2 is a rear side view thereof;

FIG. 3 is a top view thereof;

FIG. 4 is a bottom view thereof;

FIG. 5 is a left side view thereof;

FIG. 6 is a right side view thereof;

FIG. 7 is a front perspective view thereof; and,

FIG. 8 is a front perspective view with a front protective cap removed so that the film dispensing tool is ready for use.
